UNITED STATES PATENT OFFICE.

FRED A. RUMNEY, OF EAST SOMERVILLE, MASSACHUSETTS, ASSIGNOR TO UNITED SHOE MACHINERY COMPANY, OF PATERSON, NEW JERSEY, A CORPORATION OF NEW JERSEY.

MACHINE FOR SETTING EYELETS.

SPECIFICATION forming part of Letters Patent No. 707,644, dated August 26, 1902.

Application filed March 7, 1901. Serial No. 50,240. (No model.)

To all whom it may concern:

Be it known that I, FRED A. RUMNEY, a citizen of the United States, residing at East Somerville, in the county of Middlesex and State 5 of Massachusetts, have invented certain new and useful Improvements in Machines for Setting Eyelets; and I do hereby declare the following to be a full, clear, and exact description of the invention, such as will enable others 10 skilled in the art to which it appertains to make and use the same.

The present invention relates to machines for setting eyelets, rivets, lacing hooks or studs, and similar articles.

15 More particularly the present invention relates to eyeleting or analogous machines in which a punch is employed to form a hole in the work to receive the eyelet or other article to be secured thereto.

20 The objects of my invention are to provide a machine of the type referred to which shall be efficient in operation, which can be operated at a high rate of speed, and which shall be simple in construction and mode of operation. To accomplish these results, it has been proposed to utilize the shoulder of the 25 punch which forms the hole in the work to receive the eyelet as a clenching-surface or setting-die, thereby eliminating from the machine mechanism for separately actuating one 30 of the dies, with a consequent simplification in the construction and an increase in the speed of operation.

The machine above referred to is of comparatively simple construction and is rapid in operation; but in practical use its efficiency is seriously impaired by certain inherent defects in its underlying principle of organization and mode of operation. Since the shoulder 35 of the punch constitutes one of the setting-dies, in the operation of the machine the eyelets must be forced over the punch, which remains in the hole formed in the work, in order to be clenched or set against the shoulder 40 of the punch. As a result of this construction and mode of operation the cutting edge of the punch is unprotected during the setting of the eyelet, and if the eyelet is slightly out of position or imperfect, as is frequently the case, it is forced against the cut-

ting edge of the punch, which is thereby dulled or nicked sufficiently to destroy its usefulness. The punch employed is tubular, and it often happens that an eyelet smaller than the average is forced inside instead of 55 outside of the punch, thereby rendering the machine inoperative and breaking the punch. The cutting edge of the punch is also often dulled or nicked by contact therewith of the eyelet-retaining spindle of the coöperating 60 setting-die. Another defect in the operation of the machine above referred to is due to the fact that the hole formed in the material is necessarily smaller than the tubular portion of the eyelet, since the eyelet is forced 65 over the punch during the setting operation. As a result of forming the hole smaller than the tubular portion of the eyelet the work often presents a wrinkled or puckered appearance at the edge of the eyelet after the eyelet is set. 70

In my pending application, Serial No. 44,256, filed January 22, 1901, I have disclosed and broadly claimed an invention whereby these defects are overcome and a machine of increased efficiency is provided which is simple 75 in construction and rapid in operation. That invention, broadly stated, consists in providing an eyeleting or analogous machine with a punch, a setting-die, a coöperating die, and means for moving the setting-die into a position between its coöperating die and the punch. The machine which I have disclosed 80 in said application is provided with a divided setting-die, the parts of which move toward each other until they come in contact in a 85 position between the coöperating die and the punch. This construction of setting-die is open to the objection that the parts of the die may be prevented from coming closely in contact by dirt or foreign substance accumulating between them or by a fold of the work being operated upon. Also the eyelet-retaining spindle of the coöperating die has a tendency 90 to separate the parts of the setting-die. In accordance with my present invention I 95 employ an integral or undivided die, whereby the objections above noted are obviated and the construction is simplified; and a feature of my invention consists in providing an eyeleting or analogous machine with a punch, 100

an integral setting-die, a coöperating die, and means for moving the setting-die into a position between its coöperating die and the punch.

5 In order to prevent the work being displaced during the setting operation, it is necessary that the setting-die be brought close to the surface of the work prior to the setting of the eyelet, and in order to allow the 10 work to be fed it is necessary that the setting-die be out of contact with the work during its feeding movement. To these ends a feature of my invention consists in providing an eyeleting or analogous machine comprising a punch, a setting-die, and a coöperating die with means for moving the setting-die into a position between its coöperating die and the punch and for moving the setting-die toward the work. This feature of 15 my invention is not limited to any particular construction of setting-die, although in its preferred form the die is integral. As a means for supporting the setting-die during the setting operation I prefer to construct the 20 punch so as to form an abutment for the setting-die when in a position between its coöperating die and the punch, and I also prefer to actuate the punch to move the setting-die toward the work, and certain features of my 25 invention consist in constructing and arranging the parts to so operate. As in the machine of the prior art above referred to and in the machine disclosed in my pending application, I prefer to employ the punch to feed the 30 work, and certain features of my invention consist in providing an eyeleting-machine comprising a punch acting to feed the work with the devices and combinations of devices hereinafter described and claimed, the 35 advantages of which will be obvious to those skilled in the art.

A machine embodying my present invention possesses the advantages of the machine disclosed in my pending application, in that 40 the punch may be constructed to form a hole of any desired size in the work regardless of the size of the eyelet, in that the setting-die is moved into a position between its coöperating die and the punch, and thereby forms 45 a protection for the cutting edge of the punch to prevent the contact therewith of an eyelet or the eyelet-retaining spindle or any portion of the coöperating die, and in that the machine can be operated at a high rate of speed, 50 since the setting-die can move into line with its coöperating die as soon as the punch leaves the work. A machine embodying my present invention also possesses the additional 55 advantages of being provided with an integral setting-die, whereby the efficiency of the machine is increased and its construction simplified, and of being provided with means for moving the setting-die toward the work, 60 whereby any displacement of the work during the setting operation is avoided.

A preferred form of my invention is illus-

trated in the accompanying drawings, in which—

Figure 1 is a view in side elevation of an eyeleting-machine embodying the same, the 70 mechanism for feeding the eyelets being omitted. Fig. 2 is a view in rear elevation of the machine shown in Fig. 1, a portion of the machine being broken away to show underlying parts. Fig. 3 is a detail plan view of the 75 work-supporting table, the presser-foot, and the setting-die. Figs. 4, 5, 6, 7, and 8 are detail views, somewhat diagrammatic, illustrating the operation of the punch and dies in forming a hole in the work and setting an 80 eyelet.

Referring to the drawings, 1 indicates the frame of the machine, and 2 a driving-shaft mounted in suitable bearings in the lower portion thereof. To the shaft 2 are secured a 85 driving-pulley 3, a cam-disk 4, a block 5, and a crank-disk 6, from the three latter of which the moving parts of the machine are operated, as will be hereinafter described.

7 represents the lower setting-die, secured 90 in the upper end of a rod 8, mounted to reciprocate vertically in suitable bearings at the front of the machine-frame. The rod 8 is reciprocated from the crank-disk 6 by means of a block 9, seated in a transverse slot in an 95 enlargement of the rod 8 and loosely mounted upon the crank-pin 10. 11 designates a lever mounted upon a horizontal pivot at the upper end of a vertical shaft or rod 12, swivelingly mounted in the machine-frame. The 100 lower end of the shaft 12 is provided with a nut 13, between which and the bearing for the shaft a strong spiral spring 14 is interposed. The rear end of the lever 11 extends through a slot in the yoke 15 at the upper end 105 of a vertical rod 16, mounted to reciprocate in a bearing at the rear of the machine-frame. The lower end of the rod 16 is provided with a roll 17, which engages a cam-groove 18, cut in the rear face of a cam-disk 4. The rod 16 110 is reciprocated by means of the cam-groove 18, and through the engagement of the rear end of lever 11 with the slot in the yoke 15 vertical oscillating movements are imparted to the lever. For swinging the lever 11 laterally with 115 the shaft 12 as a pivot a lever 19 is pivoted upon a horizontal pivot 20 at one side of the machine-frame, the lower end of which is provided with a roll which engages a cam-groove 120 cut in the front face of the disk 4, and the upper end of which extends into a position to bear against an adjustable stop-screw 21, projecting laterally from the rear end of lever 11. To hold the stop-screw 21 in contact with the upper end of the lever 19, a spiral 125 spring 22 is provided, which connects the rear end of lever 11 with the lateral extension 23 of the upper end of lever 19. Screwing through one end of the yoke 15 is an adjustable stop-screw 24, which limits the movement of the rear end of lever 11 in one direction. The spring 22 tends to hold the stop- 130

screw 21 in contact with the upper end of lever 19, but permits the lever to move away from the stop-screw when the lever 11 contacts with the adjustable stop 24. By adjusting the stop-screws 21 and 24 the extent of the lateral movements imparted to lever 11 may be varied as desired.

The mechanism so far described, with the exception of the shape of the cam-groove 18, is the same as that of the well-known Hawkins eyeletting - machine, such mechanism constituting suitable and efficient means for producing the desired movements of the lower setting-die and the punch. In the Hawkins machine the upper setting-die is mounted on the front end of the lever 11 and is actuated by the lever to enter the hole previously punched in the material by a separate punch and feed the material into a position to bring the hole directly over the lower die 7. In utilizing the mechanism of the Hawkins machine in carrying out my present invention I mount the punch in the front end of the lever 11, the punch being indicated at 25. The cam-groove 18 is shaped to impart to the punch 25 a downward movement to punch a hole in the material and thereafter to slightly raise the same to clear the work-supporting table without withdrawing it from the work. The cam 18 then acts to hold the punch so raised while the punch is moved by the action of the lever 19 on lever 11 to feed the work and bring the hole punched therein directly over the lower die 7. The cam 18 then acts to raise the punch and then depresses it slightly and holds it in this position during the setting operation for a purpose which will be hereinafter described. The cam-groove then acts to raise the punch, 40 which is returned to its original position by the action of the lever 19 and spring 22 on lever 11. For supporting the work during the punching, feeding, and eyelet-setting operations a horizontal table 26 is provided, secured to the upper part of the front portion of the machine-frame. The punch, which is tubular, cuts against the surface of this table or against a cutting-block set therein, and the table is provided with an opening for the 45 passage of the lower setting-die therethrough. An adjustable gage 27 is secured to the upper surface of the table in a position to engage the edge of the work as it is fed by the punch.

In the embodiment of my invention illustrated in the drawings the upper setting-die 28 is integral or undivided and is secured to or forms a part of the free end of an arm 29, projecting horizontally over the table 26 from a sleeve 30, loosely mounted upon the upper 50 end of a vertical rod 31, rigidly clamped at one side of the front portion of the machine-frame. Surrounding the rod 31 is a coiled spring 32, one end of which is secured to a collar 33, fast on the rod, and the other end 55 of which is secured to the sleeve 30. This spring acts to swing the arm 29 to bring the setting-die 28 in line with the coöperating die

7, the movement of the arm under the tension of the spring being limited by a stop-pin 34, projecting downwardly from the sleeve 30, which contacts with a stop-pin 35, projecting upwardly from the collar 33. The collar 33 is adjustably secured to the rod 31 by means of a set-screw 36, whereby the position of the stop-pin 35 can be adjusted to bring the setting-die 28 in alinement with its coöperating die when the pins 34 and 35 are in contact. When the die 28 is in alinement with its coöperating die, it is in the path of movement of the punch, and in order to allow the setting-die to be displaced during the feeding movement of the punch to bring the hole formed in the work directly over the die 7 the free end of arm 29 at one side of and above the setting-die is arranged to be 80 engaged by the shank or enlarged portion of punch 25. The manner in which the arm 29 is moved during the feeding movement of the punch to displace the setting-die is indicated in Fig. 3, in which the arm is shown in full lines in the position which it assumes when the setting-die is in line with its coöperating die and in dotted lines in the position which it assumes when displaced by the punch. As the punch rises through the 85 action of cam-groove 18, as described above, the arm 29 is actuated by spring 32 to return the setting-die to its original position in line with its coöperating die, in which position it is between its coöperating die and the punch. 90 In order to allow the setting-die to move to this position as soon as the punch is raised from the work, a slot 37 is formed on the upper side of the arm 29 directly over the setting-die, into which the reduced portion of the 95 punch passes as soon as the enlarged portion has been raised above the upper surface of the lever. In order to prevent the work from being displaced upwardly during the setting of the eyelet, it is necessary that the setting-die be in close proximity to the work during the setting operation. To allow the work to be fed, however, it is necessary that the setting-die be above the surface of the work during the feeding movement of the punch. To 100 accomplish these results in the construction shown in the drawings, the sleeve 30 is yieldingly held in raised position on the rod 31 by means of the coiled spring 32, the upward movement of the sleeve being limited by a 105 collar 38, secured to the rod above the sleeve. In the construction shown in the drawings the arm 29 is comparatively thin and is not of sufficient rigidity to withstand the upward pressure of the lower setting-die during the setting operation. The shoulder of the punch formed by the lower end of the enlarged portion of the punch is accordingly utilized to form an abutment for the setting-die during the setting operation by bearing against the upper 110 surface of the arm 29, the reduced portion of the punch being received in the slot 37, as above described. After the punch 25 has been raised sufficiently to allow the setting- 115

die to move to a position between its coöperating die and the punch the punch is lowered by the action of cam-groove 18, which has been described. This movement of the punch moves the setting-die into close proximity to the work, and while the die is so held depressed by the punch the lower die 7 is actuated to force an eyelet through a hole in the work and set it against the setting-die.

10 For holding the work in position upon the table 26 the presser-foot 39 is provided, secured to the upper end of a spring-pressed rod 40, mounted in suitable bearings in the machine-frame. A three-armed lever 41 (see Fig. 1) is pivoted in the lower part of the machine-frame, one arm of which extends beneath the lower end of rod 40. The vertical arm of the lever 41 extends into a position to be engaged by a pin 42 on the block 5, which is secured to the shaft 2, whereby the lever 41 is actuated to raise the presser-foot from the work during the feeding movement of the punch. The third arm of lever 41 is connected, by means of a rod or wire 43, to a treadle, (not shown,) whereby the lever 41 can be actuated to raise the presser-foot for the insertion and removal of work.

The operation of the machine above described will be clearly understood from an inspection of Figs. 4 to 8. Starting with the punch and setting-die in the position shown in Fig. 4, the punch is actuated to form a hole in the work, the cutting edge of the punch coming in contact with the upper surface of the feed-table 26 or a suitable cutting-block set therein. The punch is then raised slightly to the position shown in Fig. 6 and then moved to the left, bringing the hole formed in the work directly over the lower die. During this movement the enlarged portion of the punch engages the arm 29 and moves it to one side, thereby displacing the setting-die, the parts assuming the position shown in Fig. 6. The punch is then raised to the position shown in Fig. 7, when the arm 29 is moved by the action of spring 32 to bring the setting-die into a position between its coöperating die and the punch. In this position the shoulder of the punch bears against the upper surface of the arm 29, and the reduced portion of the punch is received in the slot 37. The punch is then depressed to move the setting-die 28 in close proximity to the work, and the lower die is actuated to carry the eyelet retained thereon by the usual eyelet-retaining spindle through the hole in the material and set it against the setting-die, as shown in Fig. 8. The parts are then returned to their original position, and the cycle of operations is repeated. During the setting operation the cutting edge of the punch is protected by the interposition of the setting-die between its coöperating die and the punch, so that neither the eyelet-retaining spindle nor other portion of the lower die can come in contact therewith, nor can an

eyelet be forced against the cutting edge of the punch.

Having thus described my invention, I claim as new and desire to secure by Letters Patent of the United States—

1. An eyeleting-machine, having, in combination, a punch, means for actuating the punch to form a hole in the work to receive an eyelet, a setting-die, a coöperating die, 75 means for moving the setting-die into a position between its coöperating die and the punch, means for moving the setting-die toward the work, and means for relatively actuating the dies to set the eyelet, substantially as described.

2. An eyeleting-machine, having, in combination, a punch, means for actuating the punch to form a hole in the work to receive an eyelet, a setting-die, a coöperating die, 85 means for moving the setting-die into a position between its coöperating die and the punch, the punch being constructed and arranged to form an abutment for the setting-die, means for actuating the punch to move 90 the setting-die toward the work, and means for actuating said coöperating die, substantially as described.

3. An eyeleting-machine, having, in combination, a punch acting to feed the work, 95 means for actuating the punch to form a hole in the work to receive an eyelet, a setting-die movable toward and from the work yieldingly mounted in the path of movement of the punch, a coöperating die, means for actuating the punch to feed the work and displace the setting-die and thereafter allow the setting-die to move to a position between its coöperating die and the punch, the punch being constructed and arranged to form an 105 abutment for the setting-die, means for actuating the punch to move the setting-die toward the work and means for actuating said coöperating die, substantially as described.

4. An eyeleting-machine, having, in combination, a punch acting to feed the work, means for actuating the punch to form a hole in the work to receive an eyelet, a setting-die, a coöperating die, means for actuating the punch to feed the work, means for moving the setting-die to a position between its coöperating die and the punch, the punch being constructed and arranged to form an 115 abutment for the setting-die, means for actuating the punch to move the setting-die toward the work, and means for actuating said coöperating die, substantially as described.

5. An eyeleting-machine, having, in combination, a punch, actuating mechanism therefor, an integral setting-die, a coöperating die, means for moving the setting-die into a position between its coöperating die and the punch and means for relatively actuating the dies to set the eyelet, substantially as described.

6. An eyeleting-machine, having, in combination, a punch, actuating mechanism

therefor, an integral setting-die, a coöperating die, means for moving the setting-die into a position between its coöperating die and the punch, and means for actuating said coöperating die, the punch being constructed and arranged to form an abutment for the setting-die during the setting operation, substantially as described.

7. An eyeleting-machine, having, in combination, a punch acting to feed the work, means for actuating the punch to form a hole in the work to receive an eyelet, an integral setting-die yieldingly mounted in the path of movement of the punch, a coöperating die, means for actuating the punch to feed the work and displace the setting-die to one side of the punch, and thereafter allow the setting-die to move to a position between its coöperating die and the punch, the punch being constructed and arranged to form an abutment for the die during the setting operation

and means for actuating said coöperating die, substantially as described.

8. An eyeleting-machine, having, in combination, a punch acting to feed the work, means for actuating the punch to form a hole in the work to receive an eyelet, an integral setting-die, a coöperating die, means for actuating the punch to feed the work, means for moving the setting-die into a position between its coöperating die and the punch, the punch being constructed and arranged to form an abutment for the setting-die, and means for actuating said coöperating die, substantially as described.

In testimony whereof I affix my signature in presence of two witnesses.

FRED A. RUMNEY.
